UNITED STATES PATENT OFFICE

DOUGLAS Z. PETERS, OF IDA GROVE, IOWA

JEWELRY DISPLAY DEVICE

Application filed June 29, 1931. Serial No. 547,768.

This invention relates to certain new and useful improvements in display devices, and the primary object of this invention is to provide a device especially adapted for displaying jewelry.

A still further object of the invention is to provide a device of the character above mentioned, which is collapsible and which may be readily set up for efficiently and attractively displaying jewelry and indicating the price thereof.

Other objects and advantages of the invention will be apparent from a study of the following description, taken in connection with the accompanying drawings wherein:

Figure 1 is a front elevational view of the device, the same being shown in position for displaying jewelry.

Figure 2 is a transverse sectional view taken substantially on the line 2-2 of Figure 1.

Figure 3 is a fragmentary detail sectional elevational view showing the means for securing the abutting edges of the side wings together.

Figure 4 is a plan view of the blank from which the device is formed.

Figure 5 is a transverse sectional view through the device as shown in Figure 1.

Figure 6 is a fragmentary detail sectional view through a portion of the top wall of the device showing the manner of suspending an article of jewelry therefrom.

With reference more in detail to the drawings, it will be seen that the device is cut from a single blank of cardboard or other suitable flexible material, and of a shape shown to advantage in Figure 4. The blank is folded on two fold lines 5-5 converged inwardly from one edge of the blank to a common center whereby to provide a front wall 6 and substantially triangular side walls or wings 7 adapted to be folded rearwardly with respect to the front wall, and have their free longitudinal edge disposed in abutting relation whereby the walls 6 and 7 provide a body substantially triangular in cross section and tapering toward the upper end thereof. One of the side wings 7 adjacent the free longitudinal edge is provided with slits 8, while the other of the side wings 7

adjacent its free edge is provided with suitable locking tongues 9 insertable through and engageable with the slots or slits 8 for securing the device in assembled relation as suggested in Figures 1 and 5.

The front wall 6 also tapers toward its upper end and merges into an upstanding card supporting extension 10 that has pressed outwardly therefrom upper and lower pairs of spaced opposed retaining fingers 11 adapted to engage a suitably shaped card 12 that tapers toward its lower end. The card 12 on the outer face thereof is adapted to have marked thereon the price of the jewelry, or other indicia relative to the articles displayed on the device.

The portion of the device formed by the front wall 6 and the side wings 7 provide a suitable support about which may be draped a necklace or the like as shown in Figure 1.

The front wall 6 has suitably located thereon suitable apertures 13 for the reception of clasps or hooks 14 forming part of such jewelry as suggested at 15.

From the foregoing then it will be seen that I have devised a device that may be readily set up or folded, when not in use, and which when set up, will display efficiently in an attractive manner jewelry such as brooches, necklaces and which is also provided with means for displaying indicia relative to the articles on display.

Even though I have herein shown and described the preferred embodiment of the invention, it is to be understood that the same is susceptible of further changes, modifications and improvements coming within the scope of the appended claims.

Having thus described my invention, what I claim as new is:

1. As a new article of manufacture, a combined display stand and sign support formed from a single blank of flexible material and including a front portion having correspondingly shaped integral upper and lower sections, a pair of wings foldable back from the sides of the lower sections, the lower front section and wings being hinged together on lines that converge toward that end of said lower front section merging with the upper

front section, said upper front section having opposite inclined edges merging with the hinge lines at the converging ends of said hinge lines, pairs of opposed card engaging fingers on said upper front sections and arranged to support an indicia bearing card having substantially the same general configuration of said upper front section.

2. A display stand including in combination a base having a side section tapering to a relatively small end as it continues from the bottom to the top of the base, said section continuing upwardly beyond the top of the base and inversely increasing in width as it approaches its upper extremity, vertically spaced pairs of opposed sign card retaining elements on the upper extended portion of said side sections, the retaining elements of the lower pair being offset inwardly towards one another from the plane of the retaining elements of the upper pair, and a sign card of substantially the same configuration as the upper extended portion of said side section insertible between the fingers longitudinally of said side section.

In testimony whereof I affix my signature.
DOUGLAS Z. PETERS.
